Inventor
HECTOR RABEZZANA

UNITED STATES PATENT OFFICE.

HECTOR RABEZZANA, OF FLINT, MICHIGAN, ASSIGNOR TO A C SPARK PLUG COMPANY, OF FLINT, MICHIGAN, A COMPANY OF MICHIGAN.

BRAIDED COVER FOR SPARK-PLUG CABLES.

Application filed October 30, 1925. Serial No. 65,791.

This invention relates to the provision of means to prevent heating of spark plugs and preignition of the explosive mixture in gas engines.

It is found that simultaneously with the closing of an electric circuit through one of the spark plug leads by the action of the distributor an induced current is produced in one or more of the adjacent cables. This may, especially in case of high speed engines, be of sufficient magnitude to cause a small spark at a second spark plug, which spark is of course not properly timed with reference to the cylinder operation of the cylinder with which this second spark is associated. This second spark may be of sufficient magnitude to cause preignition, but even if not, it has been found troublesome in that it serves to heat the spark plug. A continuation of this secondary sparking results in undesirably raising the temperature of spark plugs as a whole.

It is an object of this invention to prevent this secondary sparking to prevent preignition and to keep down the excessive temperature of the spark plugs by preventing the induced currents in the electric cables adjacent to the cable acting to fire its charge. This object is accomplished by enclosing each cable with a metal sheath, and grounding this metal sheath on the engine block.

In the drawing accompanying this specification is shown a practical embodiment of the idea. In Figure 1 is shown in side elevation an explosive engine equipped with my invention.

Figure 2 shows diagrammatically the wiring and grounding arrangement for the cable sheath. Figure 3 shows in side elevation a modified form of engine having my invention employed therewith. Figure 4 is a side view of one of the electric cables equipped with my metallic sheath.

Referring to the drawing, numeral 1 represents an explosive engine having at one end thereof the clutch housing 2. At the opposite end of the engine is shown the generator 3 with the coil 4 mounted above the same. Centrally disposed on the engine is shown the carburetor 5, the intake manifold 6 and the exhaust manifold 7. Above the engine block is seen the distributor 8 and the water tubing 9. Connecting the coil 4 and the distributor

8 is the usual electric cable 10, and from the distributor 8 are the several leads 11 extending one to each of the spark plugs 12.

In making these usual electric connections the several leads from the distributor to the spark plugs must necessarily be located quite closely to each other, especially in the vicinity of the distributor. Owing to the close relationship of these leads, when the current is passing in one of them to cause the explosion of the mixture in any one cylinder, induced currents occur in one or more of the other cables. As explained above these induced currents may cause preignition and are known to cause objectionable heating of the spark plugs. To prevent these results each of the cables 11 is covered with a metal sheath as shown at 13 in Figure 4. This metal sheath may be of various constructions but it is preferred to make it of woven strands of wire. These coverings are grounded to the engine block by individual wires connected thereto and to the engine block as shown at 17 in Figure 1.

In Figure 2 the grounded connection is illustrated diagrammatically. The several leads from the distributor being shown, each with its grounded connection with a circle drawn to illustrate the ground.

Figure 3 shows another form of gas engine. Here the only essential difference consists in the location of the wiring. In this figure the distributor is shown closely adjacent the generator 3 and the leads 11 from the distributor extends up side by side and into a metallic cylindrical member 14 which is grounded to the engine block by its metallic support 15. The member 14 has the necessary outlets for the leads extending to the spark plugs as will be readily understood. In this type of motor instead of employing a separate wire from each lead and connecting said wire to the motor block, the metallic sheath of the lead is grounded by engagement with member 14 and its metallic support 15.

By the provision of the arrangements described above the objectionable induction currents are prevented.

Attention is also called to the fact that if the future development of radio extends to the use of shorter wave lengths the point may soon be reached where the radio wave length will be the same as that of spark plugs, in

which event the automobile spark plug would cause considerable interference. This is another advantage resulting from the use of this metallic sheath.

5 I claim:

In combination with an explosive engine, a plurality of spark plugs, a distributor, a plu-

rality of leads from said distributor to said spark plugs, each lead being an insulated wire and having a metal sheath surrounding its insulation and a ground for each metal sheath.

In testimony whereof I affix my signature.
HECTOR RABEZZANA.
